Primary Examiner — Phillip S Hyder*(74) Attorney, Agent, or Firm* — Blakely, Sokoloff, Taylor & Zafman LLP(57) **CLAIM**

The ornamental design for an abdomen developing exerciser, as shown and described.

DESCRIPTION

FIG. 1 is a perspective view showing the new design for an abdomen developing exerciser;

FIG. 2 is an enlarged front view thereof;

FIG. 3 is an enlarged rear view thereof;

FIG. 4 is an enlarged right side view thereof;

FIG. 5 is an enlarged left side view thereof;

FIG. 6 is an enlarged top view thereof; and,

FIG. 7 is an enlarged bottom view thereof.

Broken lines illustrate portions of the abdomen developing exerciser outside the scope of the claimed design.
